UNITED STATES PATENT OFFICE.

ELMER B. STONE, OF NEW BRITAIN, CONNECTICUT, ASSIGNOR TO AMERICAN HARDWARE CORPORATION, OF NEW BRITAIN, CONNECTICUT, A CORPORATION OF CONNECTICUT.

DESIGN FOR A PADLOCK.

54,874.

Specification for Design.

Patented Apr. 13, 1920.

Application filed September 7, 1918. Serial No. 253,081. Term of patent 14 years.

To all whom it may concern:

Be it known that I, ELMER B. STONE, a citizen of the United States, residing at New Britain, in the county of Hartford and State of Connecticut, have invented a new, original, and ornamental Design for a Padlock, of which the following is a specification, reference being had to the accompanying drawings, forming part hereof, in which—

Figure 1 is a face view of a padlock showing my new design.

Fig. 2 is a top view of the same with the bow cut in section.

Fig. 3 is a view in lengthwise section through the same, for a portion of the distance from the top downwardly.

Fig. 4 is an edge view of my improved padlock.

I claim:

The ornamental design for a padlock as shown.

ELMER B. STONE.
